HOWARD H. JOHNSTON, OF EDGEWOOD PARK, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

1,412,528.

Specification of Letters Patent. Patented Apr. 11, 1922.

Application filed June 9, 1919. Serial No. 302,756.

To all whom it may concern:

Be it known that I, HOWARD H. JOHNSTON, a citizen of the United States, and a resident of Edgewood Park, in the county of 5 Allegheny and State of Pennsylvania, have invented a new and useful Improvement in Systems of Control, of which the following is a specification.

My invention relates to systems of control and it has special relation to the control of industrial locomotives or the like that may be governed both from within the vehicle and from a tower or control room alongside the track.

15 In connection with the loading of coal cars from overhead bins by means of the familiar chute method, it is impossible for an operator upon the locomotive to determine the proper distance to move the train, as 20 each car is filled, in order to place the succeeding car under the coal chute. However, such control of the train may readily be effected from a tower or control room near the coal-loading apparatus.

25 It is an object of my invention, therefore, to provide a combined control system for industrial locomotives whereby the operation thereof during the hauling of full or empty cars may be governed from an operator's stand within the vehicle, whereas, 30 during the above-mentioned loading operation, the movements of the train, both in direction and magnitude, may be controlled from a tower near the track.

35 Another object of my invention is to provide a positive and a negative third-rail shoe or current-collector for use in connection with both the main and the auxiliary control circuits of a locomotive, together 40 with another shoe or current-collector that may be energized, either positively or negatively, to determine the direction of operation of the electric locomotive during either type of control of the locomotive, 45 that is, either from within or without the vehicle.

Another object of my invention is to provide a plurality of relay devices that are associated with the above-mentioned current collectors and the reverser-control apparatus for the propelling motors in such manner that one or another of the relay devices shall be energized to effect the opera-

tion of the proper switching apparatus to ensure the desired direction of movement 55 of the vehicle.

Another object of my invention is to provide means for effecting the actuation of the directional control switches immediately upon the energization of the above-mentioned relay devices when tower control is utilized, under which conditions the reversing and accelerating control apparatus in the locomotive are placed in disconnected or inoperative positions.

65 A further object of my invention is to provide a system of the class under consideration wherein automatic acceleration of the propelling motors, through a predetermined number of steps, is effected when operating from the tower, whereas, partial automatic operation and partial hand operation are provided when the locomotive is operated from its own cab.

70 Another object of my invention is to provide suitable electrical interlocking between the various switches and the relay devices so that the proper sequence of operation is ensured and also relatively low potentials are employed in the auxiliary control system to decrease the necessary amount of insulating material and the degree of burning of the interlock contact segments and fingers.

75 Other objects of my invention will become 85 evident from the following detailed description, taken in conjunction with the accompanying drawing, wherein—

Figure 1 is a diagrammatic view of the main circuits of a system of control employed in connection with my invention;

90 Fig. 2 is a diagrammatic view of the auxiliary governing circuits for the system that is shown in Fig. 1; and

95 Fig. 3 is a sequence chart of well-known form for indicating the proper order of operation of the various illustrated controlling switches.

100 Referring to Fig. 1 of the drawing, the main system here shown comprises suitable supply-circuit conductors, such as third-rails 11 and 12, for supplying energy, through over-running third-rail shoes or other current-collecting devices 11' and 12', to a plurality of electric motors respectively having 105 commutator-type armatures A1 and A2 and

series field windings F1 and F2. A plurality of accelerating resistors 9 and 10 and controlling switches LS1, LS2, S, G1, G2, R1 to R6, inclusive, and 1 to 8, inclusive, are employed to govern the acceleration of the motors during both series and parallel operation thereof. A limit switch or current relay 14 is also provided to effect automatic control of the system under predetermined 10 conditions, in accordance with a familiar practice.

The auxiliary system shown in Fig. 2 comprises actuating coils for the various switches that are shown in Fig. 1, together with electrical interlocks or auxiliary contact members that are actuated by certain of the switches, in accordance with the familiar construction that is shown in connection with the switch LS2 in Fig. 1, and, in addition, a master controller MC, having a plurality of operative positions *a* to *z*, inclusive, a master reverser MR, a cutout switch 15, a tower controller 15a, a plurality of relay devices 16 and 17 of the double-disk 25 type and a control resistor 18 are provided for selectively governing the operation of the various switches in accordance with the sequence that is indicated by Fig. 3. In addition to the supply-circuit conductors 30 11 and 12, a third supply conductor 13, which may be engaged by an under-running shoe 13', is provided for effecting a certain portion of the locomotive control and is adapted to assume either positive or negative polarity, in accordance with the will of the operator, for purposes to be set forth.

Assuming that it is desired to effect operation of the locomotive during the hauling period when control from within the locomotive cab is most suitable, the cutout switch 15 may occupy either its illustrated off position or the position marked "Cab", while the master reverser MR initially occupies its off position.

Upon movement of the master controller MC to its initial operative position *a*, one circuit is established from the positive supply-circuit conductor 11 through shoe 11', conductor 20, train-line conductor 21, conductors 22 and 23, control fingers 24 and 25, which are bridged by contact segment 26 of the master controller, conductor 27, train-line conductor 28, conductor 29, resistor 30, actuating coil 31 of the relay device 17, conductor 32, train-line conductor 33 and conductor 34, to the current-collecting device 13' and the associated stationary conductor 13, which, under the present inoperative conditions, therefore, is of positive polarity. However, the circuit just traced is not completed until the master reverser MR is actuated to the one or the other of its operative positions, as subsequently described in detail.

A further circuit is continued from the conductor 29 through conductors 40 and 41,

control resistor 18, conductors 42, 43, 44 and 45, control fingers 46 and 47, which are bridged by contact segment 48 of the master controller, conductors 49 and 50, train-line conductor 51, conductor 52 and shoe 12' to the negative supply-circuit conductor 12. The control resistor 18 is thus connected between the positive and negative supply-circuit conductors and is employed to provide suitably low operating voltages, by means of 75 properly placed taps, to the actuating coils for the various switches.

If the master reverser MR is now moved to its forward position, a new circuit is continued from the conductor 50 through contact segment 38 of the master reverser and conductor 39 to the train-line conductor 33, whereby the auxiliary current-collecting device 13' and the directly-connected circuits are made of negative polarity corresponding to that of the conductor 50. Consequently, the circuit previously traced through the actuating coil 31 of the relay device 17 is energized to cause the relay device to assume its upper position. 90

Under such conditions, a circuit is established from an intermediate tap-point 53 of the control resistor 18 through conductors 54, 55, 56 and 57, lower contact disk 58 of the relay device 17, in its upper position, 95 conductors 59, upper contact disk 60 of the relay device 16, in its normal or lower position, conductor 61, the parallel-related actuating coils of the switches 2 and 4, and interlock 1-out to conductor 62, a branch circuit 100 being also energized and traversing the parallel-related actuating coils of the switches 6 and 8 and interlock 5-out to the conductor 62, whence a common circuit is completed through conductor 63 to the negative conductor 42.

The directional switches 2, 4, 6 and 8, corresponding to forward operation, are thus closed, as indicated by the corresponding circles in step *a* of the sequence chart, Fig. 3. 110

Upon the closure of the switches 4 and 8, a further circuit is completed from the conductor 40 through resistor 64, an actuating coil marked "Brake release", series-connected interlocks 4-in and 8-in and conductor 115 65 to negative conductor 44. In this way, the electric or electro-pneumatic brakes with which the vehicle is equipped are automatically released as soon as the directional switches 4 and 8 are closed and before the 120 line switch LS1 is closed to connect the motors to the supply circuit.

Another circuit is established, at this time, from a second intermediate tap-point 66 of the control resistor 18 through conductor 67, 125 interlock LS2-out, actuating coil of the switch S, interlock G2-out, and conductors 68, 55 and 54 to the tap-point 53 of the control resistor 18.

The switch S is thus closed previous to the 130

connection of the motors to the supply circuit, which may be accomplished by actuating the master controller to its position *b*.

In position *b*, a new circuit is established 5 from the tap conductor 67 through conductor 69, parallel-related actuating coils of the switches LS1 and G1, conductor 70, a suitable "Brakes-Released" interlock, train-line conductor 71, conductor 72, control fingers 73 and 74, which are bridged by contact segment 75 of the master controller, conductor 76, train-line conductor 77 and conductors 78, 56, 55 and 54 to the tap-point 53 of the control resistor 18.

15 The motors are thus connected, in series relation with the accelerating resistors 9 and 10, across the supply circuit, in accordance with the following series of connections: from the positive supply-circuit conductor 20 11 through shoe 11', switch LS1, the entire accelerating resistor 9, armature A1, switch 2, field winding F1, switch 4, conductor 35, actuating coil of the current relay or limit switch 14, junction-point 36, switch S, the 25 entire accelerating resistor 10, armature A2, switch 6, field winding F2, switches 8 and G1 and conductor 37 to the negative current-collecting device 12'.

Upon the closure of the line switch LS1, 30 a new auxiliary circuit is established from the tap-conductor 54 through conductors 55, 68 and 80, contact disk 81 of the current relay 14, when the motor current has decreased to a value corresponding to the lower position 35 of the limit switch, whence circuit is continued through conductor 82, interlocks LS1-in and R1-out, conductor 83 and the actuating coil of the resistor-short-circuiting switch R1, to negative conductor 43.

40 As soon as the switch R1 has closed, an interlock R1-in is connected in series relation with an interlock LS1-in between the tap-conductor 54 and the positive terminal of the actuating coil, whereby the switch is subsequently maintained closed, irrespective of 45 the condition of the limit switch 14.

When the current relay 14 has again dropped to its lower position, a progression circuit is established from the conductor 82 50 through interlocks LS1-in, R1-in, R2-out and the actuating coil of the resistor-short-circuiting switch R2 to negative conductor 63.

A holding interlock R2-in serves to connect 55 interlock LS1-in and the tap conductor 54 directly to the actuating coil of the switch R2, as soon as the switch has closed.

When the current relay 14 again assumes 60 its lower position, a circuit is established from the conductor 82 through interlocks LS1-in, R1-in, R2-in and R3-out, whence circuit is continued through the actuating coil of the resistor-short-circuiting switch R3 to the negative conductor 63. Upon the closure 65 of the switch, a holding interlock R3-in is

connected in circuit similarly to the previously mentioned holding interlocks R1-in and R2-in.

The accelerating resistor 9 is thus gradually short-circuited, through the automatic 70 action of the current relay 14, to effect a predetermined degree of acceleration of the propelling motors, the master controller MC remaining in position *b* throughout such automatic accelerating period. 75

Upon movement of the master controller to its position *c*, the contact segment 75 engages control finger 84, whence circuit is completed through conductor 85, train-line conductor 86, conductor 87 and the actuating coil for the switch R4 to negative conductor 63. 80

In a similar manner, contact segment 75 successively engages control fingers 88 and 89 in positions *d* and *e* of the master controller to energize conductors 90 and 91 and the actuating coils for the switches R5 and R6, respectively. The other accelerating resistor 10 is thus gradually short-circuited by hand operation, that is, by successive movements of the master controller MC, and, consequently, the motors are connected in full-series relation, corresponding to position *e* of the master controller. 90

To effect the transition of the motors to 95 parallel relation, the master controller is moved, through its transition position, to the initial parallel position *f*. In the first place, the switches R4, R5 and R6 are opened by reason of the de-energization of the corresponding control fingers 84, 88 and 89 of the master controller. In this way the accelerating resistor 10 is included in circuit with the armature A2 during the transitional and the initial parallel operating periods. 100

105 Furthermore, during the transition, a new auxiliary circuit is established from the tap-conductor 67 through conductor 92, actuating coil of the switch G2, conductor 93, train-line conductor 94, conductor 95 and control finger 96, which is engaged by the master-controller contact segment 75. The switch G2 is thus closed to effect the closure of a temporary "shunting" circuit including the resistor 10 around the armature A2 and field winding F2. 110

In addition, the actuating coil of the switch S is opened, as soon as the switch G2 is closed, by reason of the exclusion from the energizing circuit of the actuating coil for 115 the switch S of the interlock G2-out.

As soon as the switch S has opened, a further auxiliary circuit is established from the conductor 92, through interlock S-out and the actuating coil of the switch LS2 to conductor 93. 120

In this way, the series-connecting switch S is opened, while the parallel-connecting line switch LS2 is closed. The main circuits, at this time, may be traced as follows. One 130

circuit is established from the positive current-collecting device 11' through switches LS1, R1, R3 and R5, armature A1, switch 2, field winding F1, switch 4, conductor 35, actuating coil of the current relay 14, junction-point 36, conductor 100, switch G2 and conductor 37 to the negative shoe 12'. A branch circuit includes conductor 101, switch LS2, accelerating resistor 10, armature A2, switch 6, field winding F2, switches 8 and G1 and negative conductor 37. The main machines are thus connected in parallel relation, the resistor 10 being connected in circuit with the machine having the armature A2.

In positions *g*, *h* and *i* of the master controller, the contact fingers 84, 88 and 89 are again successively engaged by the contact segment 75, whereby the switches R4, R5 and R6 are closed in that order to gradually short-circuit the resistor 10.

Whenever reverse operation of the locomotive (at rest) from the cab thereof is desired, the master controller is moved to its initial position *a*, and the master reverser 25 MR is actuated from its "off" to its reverse position "Rev." Consequently, a circuit is established from the positive current-collecting device 11' through conductor 20, train-line conductor 21, conductors 22 and 102, contact segment 103, corresponding to reverse position of the master reverser, conductor 39, train-line conductor 33, and conductor 34 to the auxiliary contact shoe 13', which, in the present instance, is thus made 35 of positive polarity, which is the opposite to that assumed when forward operation of the vehicle was to be effected. In other words, the auxiliary shoe 13' is oppositely energized in accordance with, and to determine the direction of, operation of the vehicle.

Since conductors 29 and 32 are now both of positive polarity, no movement of the relay device 17 occurs, as was the case during forward operation of the vehicle. However, 45 a new circuit is established from the positively energized conductor 32 through conductor 104, actuating coil 105 of the relay device 16, a resistor 106 and conductor 44, whence circuit is completed, as already 50 traced, to the negative contact shoe 12'.

In this way, the relay device 16 is actuated to its upper position to complete a circuit from tap-conductor 54 through conductors 55, 56 and 57, contact disk 108 of the relay 55 device 17, in its normal lower position, conductor 109, contact disk 110 of the energized relay device 16 in its upper position, conductor 111, parallel-related actuating coils of the switches 1 and 3, and interlock 2-out to conductor 112, a branch circuit including parallel-related actuating coils of the switches 5 and 7 and interlock 6-out to the conductor 112, whence a common circuit is completed through conductors 62 and 63 to 60 the negative terminal of the control resistor 65

18, as previously set forth. Consequently, the directional switches 1, 3, 5 and 7, corresponding to reverse operation of the vehicle, are closed, as indicated by the crosses in step *a* of the sequence chart, Fig. 3.

It is believed that the function of the switches 1, 3, 5 and 7, whereby the connection of the field windings, with respect to the corresponding armatures of the main system shown in Fig. 1, are reversed, will be readily understood without requiring a detailed tracing of the main circuits.

Upon the closure of switches 3 and 7, the circuit of the brake-release magnet is completed through interlocks 3-in and 7-in, 80 which bridge the interlocks 4-in and 8-in described above in connection with forward operation of the vehicle. The remaining operation of the system from the locomotive cab to effect complete series-parallel connections of the propelling motors is identical with that already set forth, and no further exposition thereof need be given here.

Under the leading conditions of the train as previously mentioned, the control thereof is effected from a station or tower near the loading apparatus. The train operator, therefore, returns the master controller and the master reverser to the illustrated "off" positions and actuates the cut-out switch 15 95 to its position "Tower."

If it is then desired to effect a forward operation of the train to properly "spot" a car that is to be loaded, the tower operator actuates the switch or controller 15a into its 100 forward position.

A circuit is thereby established from the negative supply conductor 12 through conductor 116, contact segment 119 of the tower controller and conductor 117 to the auxiliary 105 supply-circuit conductor 13, whereby the auxiliary contact shoe 13' is made of negative polarity, as was the case when forward operation of the vehicle from within the locomotive cab was effected.

Upon the negative energization of the contact shoe 13' and the directly associated circuits, a circuit in the locomotive is established from the positive current-collecting device 11', through conductor 20, train-line 115 conductor 21, conductors 22 and 120, control fingers 121 and 122, which are bridged by contact segment 123 of the cutout switch 15, whence circuit is completed through conductors 123a and 27, train-line conductor 28 120 and conductor 29, to the actuating coil 31 of the relay device 17, corresponding to forward vehicle operation, which coil is connected to the auxiliary contact shoe 13'. Since this shoe has been made of negative 125 polarity by reason of the previously-described actuation of the tower controller 15a, the relay device 17 is actuated to its upper position immediately upon the operation of the tower controller and, consequently, the 130

forward directional switches 2, 4, 6 and 8 are closed.

Likewise, the control resistor 18 is energized by reason of its connection to the positively energized conductor 29, and the switch S is, therefore, closed in accordance with the previously-traced circuits. The brake-release coil is also energized, at this time, by reason of the energization of the 10 previously-traced circuit from the conductor 29 through the coil to conductor 44 which, in the present case, is directly connected to negative conductor 50 by means of a contact segment 124 upon the cutout switch 15.

Furthermore, the energizing circuit for the actuating coils of the switches LS1 and G1, one end of which circuit is connected to the tap-conductor 67, is continued as far as 20 conductor 72, in accordance with the previous description thereof, whence direct connection to conductor 76 is made by means of a contact segment 125 of the cutout switch 15. Consequently, the switches LS1 and G1 25 are closed to connect the machines in series relation with the accelerating resistors 9 and 10, across the supply circuit.

Upon the closure of the line switch LS1, the previously-described automatic progressive 30 operation of the resistor-short-circuiting switches R1, R2 and R3, in accordance with the movements of the limit switch 14, is again effected.

The automatic operation of the system to 35 the stage just described is sufficient to effect the desired "spotting" of the train and, consequently, no further provision for control of the train from the tower need be made.

For effecting reverse movement of the 40 train from the tower, the controller 15a is thrown to its position "Rev." whereby the positive supply conductor 11 is connected through conductor 115, contact segment 126 and conductor 117 to the auxiliary supply 45 circuit conductor 13. In this way, the auxiliary contact shoe 13' and the directly associated circuits are made of positive polarity, corresponding to the operation of the master reverser MR in position "Rev." during the 50 operation of the locomotive from the cab thereof. It will be understood, therefore, that, in the present instance, the relay device 16 is operated to effect the closure of the directional switches 1, 3, 5 and 7 and the 55 automatic operation of the system, up to the point including the closure of the switch R3, is accomplished as already set forth.

I do not wish to be restricted to the specific circuit connections or arrangement of 60 parts herein set forth, as various modifications thereof may be made without departing from the spirit and scope of my invention. I desire, therefore, that only such limitations shall be imposed as are indicated in the appended claims.

I claim as my invention:

1. In a system of vehicle control, the combination with a dynamo-electric machine, of a single current-collecting device having different polarities during different operations 70 of the vehicle, and a plurality of constant-polarity current-collecting devices.

2. In a system of vehicle control, the combination with a dynamo-electric machine, of a plurality of constant-polarity main current-collecting devices, and a single auxiliary current-collecting device having opposite polarities to effect forward or reverse operation 75 of the machine.

3. In a system of vehicle control, the combination with a dynamo-electric machine and a plurality of supply conductors of opposite polarities, of an auxiliary conductor, and means for connecting said auxiliary conductor to the one or the other of said supply 80 conductors to effect different operations of said machine.

4. In a system of vehicle control, the combination with a dynamo-electric machine and a plurality of supply conductors of opposite 90 polarities, of an auxiliary conductor, and means comprising a reversing-controller for said machine for connecting said auxiliary conductor to the one or the other of said supply conductors to effect forward or reverse 95 operation of the vehicle.

5. In a system of vehicle control, the combination with a dynamo-electric machine, of a plurality of relay devices for respectively controlling different operations of said machine, and means for selectively actuating the one or the other of said relay devices to complete certain circuits through the remaining relay device in its normal position to inaugurate the one or the other of such 105 operations.

6. In a system of vehicle control, the combination with a dynamo-electric machine, of a plurality of relay devices for respectively controlling different operations of said machine, a plurality of supply conductors of opposite polarities, an auxiliary conductor connected to one terminal of the actuating circuits for said relay devices, and means for connecting said auxiliary conductor to the one or the other of said supply 110 conductors to actuate the corresponding relay device and inaugurate the corresponding machine operation.

7. In a system of vehicle control, the combination with a dynamo-electric machine, of a plurality of relay devices for respectively controlling the forward or reverse operation of said machine, a plurality of supply conductors of opposite polarities, an auxiliary 125 conductor connected to one terminal of the actuating circuits for said relay devices, and means comprising a reversing-controller for said machine for connecting said auxiliary conductor to the one or the other of said 130

supply conductors to actuate the corresponding relay device and inaugurate the corresponding vehicle operation.

8. In a system of vehicle control, the combination with a dynamo-electric machine, of a plurality of relay devices for respectively controlling different operations of said machine, a plurality of supply conductors of different electrical characteristics, an auxiliary conductor connected to one terminal of the actuating coils for said relay devices, and means for connecting said auxiliary conductor to the one or the other of said supply conductors to actuate the corresponding relay device and inaugurate the corresponding machine operation.

9. In a system of vehicle control, the combination with a dynamo-electric machine, of a plurality of relay devices for respectively controlling the forward or reverse operation of said machine, a plurality of supply conductors of different electrical characteristics, an auxiliary conductor connected to one terminal of the actuating coils for said relay devices, and means comprising a reversing-controller for said machine for connecting said auxiliary conductor to the one or the other of said supply conductors to actuate the corresponding relay device and inaugurate the corresponding vehicle operation.

10. In a system of vehicle control, the combination with a dynamo-electric machine, of a plurality of relay devices for respectively controlling forward and reverse operation of said machine, and means for selectively energizing the one or the other relay device to complete certain circuits through its energized position and the normal de-energized position of the remaining relay device to determine the direction of movement of said machine.

11. In a system of vehicle control, the combination with a dynamo-electric machine, of a plurality of relay devices for respectively controlling different operations of said machine, a plurality of supply conductors of opposite polarities, an auxiliary conductor connected to one terminal of the actuating circuits for said relay devices, and means for connecting said auxiliary conductor to the one or the other supply conductors to energize the one or the other relay device and to complete certain circuits through the energized position of the corresponding relay device and the normal de-energized position of the remaining relay device.

12. In a system of vehicle control, the combination with a dynamo-electric machine, of means upon the vehicle comprising a controller for effecting operation of said machine, and means for alternatively operating the vehicle comprising a switching device upon the vehicle and a controller located outside the vehicle,

13. In a system of vehicle control, the combination with a dynamo-electric machine, of means upon the vehicle comprising a controller and a reverser for effecting operation of said machine, and means for alternatively operating the vehicle comprising a cut-out switch upon the vehicle and a controller located outside the vehicle.

14. In a system of vehicle control, the combination with a dynamo-electric machine, of a plurality of supply conductors of different electrical characteristics, an auxiliary conductor, means located upon the vehicle for connecting said auxiliary conductor to the one or the other supply conductor to effect different operations of the machine, and alternative means having switching devices located within and without the vehicle for effecting similar connections of said auxiliary conductor to effect corresponding operation of the machine.

15. In a system of vehicle control, the combination with a dynamo-electric machine, of a plurality of supply conductors of opposite polarities, an auxiliary conductor, means located upon the vehicle comprising a reverser for energizing said auxiliary conductor from the one or the other supply conductor to determine the direction of operation of said machine, and alternative means comprising a cutout switch upon the vehicle, and a controller outside the vehicle for effecting similar energization of said auxiliary conductor to effect corresponding operation of the machine.

16. In a system of vehicle control, the combination with a dynamo-electric machine, of a plurality of supply conductors of opposite polarities, an auxiliary conductor, means located upon the vehicle comprising a reverser to be thrown in the one or the other direction to effect energization of said auxiliary conductor from the one or the other supply conductor for determining the direction of operation of said machine and also comprising a multi-position controller for effecting operation of the machine, and alternative means comprising a cutout switch upon the vehicle and a controller outside the vehicle for effecting similar energization of said auxiliary conductor to immediately effect corresponding directional operation of said machine while said reverser and said controller occupy inoperative positions.

17. In a system of vehicle control, the combination with a dynamo-electric machine, of a plurality of relay devices for respectively controlling the forward or reverse operation of said machine, a plurality of supply conductors of opposite polarities, an auxiliary conductor connected to one terminal of the actuating circuits for said relay devices, means upon the vehicle comprising a reversing-controller for said machine for energizing said auxiliary conductor from

- the one or the other of said supply conductors to actuate the corresponding relay device and inaugurate the corresponding vehicle operation, and alternative means comprising a cutout switch upon the vehicle and a controller outside the vehicle for effecting similar energization of said auxiliary conductor to immediately effect actuation of the corresponding relay device and the corresponding directional operation of said machine while said reversing-controller occupies an inoperative position.
18. In a system of vehicle control, the combination with a dynamo-electric machine, of means upon the vehicle comprising a multi-position controller for effecting complete operation of said machine, and alternative means for automatically operating the machine to a certain stage comprising a switching device upon the vehicle and a controller located outside the vehicle.
19. In a system of vehicle control, the combination with an electric motor, of means upon the vehicle comprising a multi-position controller and a reverser for effecting complete acceleration of said machine, and alter-

native means for automatically operating said machine to a certain stage comprising a cutout switch upon the vehicle and a controller located outside the vehicle.

30

20. In a system of vehicle control, the combination with an electric motor, of a plurality of supply conductors of opposite polarities, an auxiliary conductor, means upon the vehicle comprising a multi-position controller and a reverser for energizing said auxiliary conductor from the one or the other supply conductor to determine the direction of operation of said machine and to effect combined automatic and manual acceleration of the machine, and alternative means comprising a cutout switch upon the vehicle and a controller outside the vehicle for effecting similar energization of said auxiliary conductor to effect automatic acceleration of said machine in a corresponding direction to a certain stage.

35

40

In testimony whereof, I have hereunto subscribed my name this 29th day of May, 1919.

45

HOWARD H. JOHNSTON.
